UNITED STATES PATENT OFFICE.

FRANK DELMONT THOMAN, OF TOLEDO, IOWA.

TRACE.

SPECIFICATION forming part of Letters Patent No. 740,948, dated October 6, 1903.

Application filed February 5, 1903. Serial No. 141,995. (No model.)

To all whom it may concern:

Be it known that I, FRANK DELMONT THOMAN, of Toledo, in the county of Tama and State of Iowa, have invented a new and useful Improvement in Traces, of which the following is a specification.

My invention relates to an improvement in traces, its object being to provide a trace which has no leather parts to wear, one which is pliable and strong, and one which can be readily attached and detached.

My invention consists of a wire-cable body portion surrounded by a tightly-coiled covering of metal and detachable hame and whiffle-tree connections.

It further consists of a wire-cable body portion surrounded by a waterproof covering, which is in turn surrounded by a tightly-coiled covering of metal, with detachable hame and whiffle-tree connections.

It further consists in certain novel constructions, arrangements, and combinations of parts, as will be hereinafter fully described, and pointed out in the claims.

In the drawings, Figure 1 is a detail central longitudinal section. Fig. 2 is a front elevation of the complete device. Fig. 3 is a transverse section through the trace-body. Fig. 4 is a detail section of one end of trace and threaded thimble. Fig. 5 is an edge view of the rear end thimble.

The trace proper is composed of a body portion composed of a wire cable A of suitable length, which has surrounding it a waterproof covering A', each end of said cable being passed through steel rings A² A² and held from passing back through said rings by having the ends enlarged or provided with caps which are greater in diameter than the opening through the said rings. Each of the rings is provided with an integral annular flange A³, surrounding the central aperture thereof. Said flanges are threaded on their outer surfaces and are adapted to screw into internally-threaded thimbles A⁴ and A⁵, the thimble A⁴ being provided with a reduced or flattened end portion a⁴, which is provided with an elongated slot a⁵, adapted to fit over the whiffle-tree-hook or other part of vehicle to which the trace is to be attached. The thimble A⁵ is provided with an integral curved

hook or lug A⁶, which is provided at or near its extremity at one side with a pin or feather a⁶, projecting therefrom.

The waterproof-covered cable is again covered with a closely-coiled spring-wire jacket A⁷, the ends a⁷ of the coiled wire being passed through the opening in the rings A² A² alongside of the cable and bent to one side against the face of the flange, thus preventing said ends from being pulled out of the rings.

The front end of the trace is to be detachably and adjustably secured to a steel tug portion B, by means of which the trace is connected with the hames. This tug portion 65 consists of the steel plate B of suitable length and thickness and is provided with a number of keyhole-openings B', placed at suitable intervals. The forward end of the plate B is adapted to be secured to the hame or collar of the animal.

It will thus be seen that I provide a simple and strong trace device which may be readily attached and detached and is strong and flexible and has no leather parts to wear and break. 75 It is particularly adapted for heavy pulling, and when the back-straps and belly-bands are attached the weight of the trace will be taken off and equally distributed.

Having thus described my invention, what I claim as new, and desire to secure by Letters Patent, is—

1. A trace comprising a body portion consisting of a wire-cable core, a coiled-spring-wire jacket surrounding said core, and end members for attachment to the whiffle-tree and hame.

2. A trace comprising a body portion consisting of a wire-cable core, a tightly-coiled spring-wire jacket surrounding said core, 90 threaded confining-rings at each end thereof, and threaded end pieces engaging said rings, said end pieces adapted for engagement with a whiffle-tree and hame respectively.

3. A trace comprising a body portion consisting of a flexible wire-cable core, a tightly-coiled spring-wire jacket surrounding said core, threaded confining-rings secured to the ends of the core and securing the ends of the coiled-wire jacket, a slotted thimble engaging the rear end ring, a thimble provided with a hook secured to the front threaded ring, a

plate engaged by the said front thimble and provided with a crook at its forward end adapted to engage a hame or collar.

4. A trace comprising a body portion consisting of a flexible wire-cable core, a waterproof covering surrounding said core, a tightly-coiled spring-wire jacket surrounding said waterproof covering, and means at the ends of said body portion for attachment to a whiffletree and harness respectively.

5. A trace comprising a body portion, consisting of a flexible wire-cable core, a waterproof covering surrounding said core, a tightly-coiled spring-wire jacket surrounding 15 said waterproof covering, threaded confining rings secured to the ends of the core, and securing the ends of the coiled-wire jacket, and

end pieces adapted for engagement with a whiffletree and harness respectively.

6. A trace comprising a body portion consisting of a flexible wire-cable core, a waterproof covering surrounding said core, a tightly-coiled spring-wire jacket surrounding 20 said waterproof covering, threaded confining rings secured to the ends of the core and securing the ends of the coiled-wire jacket which pass through the same, threaded thimbles 25 engaging the rings, said thimbles provided with means for attachment to a whiffletree and harness respectively.
